UNITED STATES PATENT OFFICE.

LEOPOLD REBEL, OF PARIS, FRANCE.

DESIGN FOR A BOTTLE FOR CONTAINING PERFUMERY.

Application filed August 6, 1926. Serial No. 18,621. Term of patent 3½ years.

To all whom it may concern:

Be it known that I, LEOPOLD REBEL, a citizen of the Republic of France, residing at Paris, France, 70 Avenue d'Iena, have invented a new, original, and ornamental Design for a Bottle for Containing Perfumery, of which the following is a specification, reference being had to the accompanying drawing, forming part thereof.

The figure is a perspective view of a bottle for containing perfumery showing my new design.

I claim:

The ornamental design for a bottle for containing perfumery, substantially as shown.

LEOPOLD REBEL.
